UNITED STATES PATENT OFFICE.

ROSCOE R. RANSOM, OF DALLAS, TEXAS.

WINDOW DISPLAY RACK.

Application filed June 16, 1924. Serial No. 720,277.

To all whom it may concern:

Be it known that I, ROSCOE R. RANSOM, citizen of the United States of America, residing at Dallas, in the county of Dallas and 5 State of Texas, have invented certain new and useful Improvements in Window Display Racks, of which the following is a specification.

This invention relates to new and useful 10 improvements in window display racks.

The object of the invention is to provide a device for displaying groceries, vegetables, sundries and the like in a show window and which may be quickly and readily inserted 15 and likewise removed.

Another object of the invention is to provide means for decorating a display window attractively and eliminating the building of shelves, racks, etc.

20 A further object of the invention is to produce a rack that is self supporting and is vertically adjustable.

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a front elevation display window showing an illustration of my invention in position,

Fig. 2 is a plan view of the same,

35 Fig. 3 is an enlarged sectional view showing the holding means, and

Fig. 4 is a sectional view taken on the line 4—4 of Fig. 3.

In the drawings the numerals 10 and 11 40 designate two curved resilient leaves whose curvatures are opposite and which may be made of any suitable material, preferably wood. The leaves are held together by means of vertical members 12 at the ends. 45 Bolts 13 pass through holes 10' and 11' in the respective leaves and receive nuts 14 at the center of the leaf 11. The holes are of greater diameter than the bolts allowing ample space for the leaves to counteract and expand without touching said bolts.

The leaves, which are made of suitable elastic wood are pulled inwardly and toward each other thereby bowed which places the leaves under tension causing the tendency to 55 expand.

A block 15 bears underneath the leaf 10

and is swingably mounted on the leaf 11 by means of hinges 16. The block acts as a brace when in an upright position thus expanding the rack, holding the same in place 60 and may be swung down as shown in dotted lines for disengagement permitting the leaves to be pressed inwardly. Recesses 15 which are adapted to receive the bolts 13 are provided thereby stopping the blocks when 65 swung upward, and assist to hold the same in engagement.

It will be seen that by grasping the center of the leaves between the bolts 13 and pressing inwardly the end member 12 will be 70 pulled away from contact with the sides of the display window A and by releasing the same a vice versa action will be effectuated.

To insert the rack in a window the blocks are swung down permitting the leaves to be 75 pressed towards each other as shown in dotted lines in Fig. 3 which allows the rack to be slid between the side walls of the display window A. After the rack is suitably located at its desired height, the 80 leaves are released causing the leaves to expand which presses the end members 12 against the side of the walls. The blocks are then swung up until stopped by bolts 13 and engage underneath the leaf 10 thereby 85 wedging themselves. The pressure exerted between the leaves due to the blocks being in a vertical position presses the rack in so tightly that ample rigidity is had to securely hold the rack a desired location.

90 The rack when in an expanded position is slightly wider than the distance between the side walls of the display window which allows the rack to fit tightly and firmly therein. It is within the scope of the invention to expand the leaves by any suitable means placed transversely therebetween.

95 It is also within the scope of the invention to fasten the rack in the window frame and not depend upon its elongation to make it 100 self supporting.

Various changes in the size and shape of the different parts, as well as modification and alterations may be made within the scope of the appended claims.

105 What I claim, is:

1. In a window display rack, a pair of flexible leaves fastened together at their ends, and means for spreading the leaves intermediate their ends to clamp the rack in a 110 window frame.

2. In a window display rack, a pair of in-

- wardly bowed flexible leaves fastened together at their ends, and means for spreading the leaves intermediate their ends to clamp the rack in a window frame.
5. In a window display rack, a pair of flexible leaves bowed inwardly toward each other and having their outer ends spaced apart and immovably secured with relation to each other, and means at the central portion of and between the leaves for spreading the leaves apart to clamp them in place.
6. In a window display rack, a pair of flexible leaves bowed inwardly toward each other, means for rigidly connecting the outer ends of the leaves, and spreader blocks engaging between the leaves to spread them apart and clamp the rack in position.
5. In a window frame display rack, a pair of flexible leaves bowed inwardly toward each other, bars connecting the ends of the leaves, spreader blocks hinged between the leaves, and bolts connecting the leaves.
6. In a show window display device, the combination with a vertical plate of glass and upright supports on each side of said plate of glass, of a pair of flexible inwardly bowed leaves disposed across said plate and having their ends secured to the upright supports, and means for spreading said leaves to clamp them between the supports in close relation to the plate.

In testimony whereof I affix my signature.

ROSCOE R. RANSOM.
